James M^o Knight

Spitter Patent

The subscriber, aforesaid to be in the city of Boston, and making part of the same, and containing a description in the words of the said James M^o Knight, himself, of his improvement in the Process of Spitting. Given

To all whence it may concern,

Be it known that I James M^o Knight of the town of Birmingham (District) of Shadfield in the state of South Carolina have invented certain new and useful improvements in the Process of Spitting. Given "the Process of Spitting" which are described as follows, reference being had to the annexed drawings of the same making part of this specification. The frame of the aforesaid spit consists of two sets, (marked A in the annexed drawings) 3 feet 6 inches long of scantling, 6 inches high, and a mortise six feet above the top of the sets to receive a cap the length of the frame of scantling, 6 inches by 4 inches by 4 inches at the top to receive a cap marked B of scantling 6 inches by 6 inches. The cap D asp is mortised to receive the aforesaid marks C. The posts to each of the bush are marked C, and to each of the sets at one end two inches in one of the aforesaid posts and a screw bolt at the other end. The posts are 3 feet 6 inches above the sets of scantling, 4 by 4 inches. The plank at the ends of the bush marked C forms a lip around the bush, and for the fulfilling board E and are 6 inches long composed of two pieces, 6 inches plank worked into the segments of a circle the lower edge fitted on the slab the upper edge having a circular cut out about one inch apart, the narrow part of the latter being held down on the upper until it comes within 3 inches of the other piece with being made fast. The comb is made of sheet iron or steel 3/4 inches wide with notches of parts the comb fastened on a board and standing yearly for formation for making use over fire with a screw below to fasten the comb to a frame the comb at the front turning on hinges. Four metal bars to which the slab are fastened. A screw D to bush A, regulating upper and lower of the bush.

A. In the yard board, P. finger board. B. trying to sit in the upper board.
 C. flat. D. comb. E. board to which the comb is fastened. The wire pins on
 which the comb stands to sit the comb. H. driving, pull, lay.
 The frame, screen, screen, basket, graining, are made in the usual manner.
 The machine is driven by horse, steam or other power. The improvement
 which I have made and desire to receive by Letters Patent consists principally
 in giving a direction to the rotation of the screen contrary to that of the common
 gin, that is the screen turns towards the feed board instead of from it.
 The advantages derived from this and the other improvements are 1. The greater portion of
 the water, salted seed, sand and trash being thus discharged before the picked
 cotton reaches the amount of four about this basket. The picked cotton consequently
 keeps clean from the gin, while on the other hand in the common gin a great
 portion of sand, water, salted seed, and trash having to pass directly through the
 current of air when the picked cotton is floating, mixes with it and in consequence
 of a part of the cotton either sinks down with the trash on the back side and
 passes with the cotton through the frame. 2. The seed are discharged as soon
 as picked, while in the common gin the seed has to pass round to where the seed
 cotton is put in, and, some time is always consumed that ought to be discharged. By which
 means the seed is able to be discharged in an irregular manner; 3. the weight of a large
 roll of cotton lies directly on the seed, which roll cannot be broken by one feeding
 or a sudden jerk of the agricultural vehicle in the common gin the roll being broken
 before the seed is raised up and falls forward causing it to become hollow
 and once feeding or a sudden jerk of the agricultural vehicle often the seed is lost.
 4. The picking in this machine being done on the account of the wire which has sub-
 stances finding its way to the seeds cannot remain there nor injure the teeth
 which in the common gin the hard substances separate from the cotton and
 lodging, against the seeds often destroying a number of the teeth and sometimes
 the teeth altogether are destroyed. 5. The upper finger board on the common gin
 is fixed and stationary having a neck and comb behind it which by pressing against
 the roll when the gin is in motion tears off the seed freely and with great regular-
 ity, while in the common gin the feed board being movable neither to the seed
 nor with too much cotton on it only restraining the seed by laying the cotton is
 slowly ground thus occasioning a loss of cotton or a loss of time. 6. The seeds, after

False seed, mostly, smooth leafs and other leafs pop out with the seed and no good cotton is lost in any way; while in the common gin smooth cotton is melted and lost and comparatively imperfected cleaned from the cotton after stated, which causes an evidently enormous loss to the improvement now made in the cotton gin.
